SUCTION CLEANER

Filed April 18, 1929

INVENTOR.

Walter C. Davidson

BY

Harry S. Dumaresq

ATTORNEY.

UNITED STATES PATENT OFFICE

WALTER C. DAVIDSON, OF NORTH CANTON, OHIO, ASSIGNOR TO THE HOOVER COMPANY,
A CORPORATION OF OHIO

SUCTION CLEANER

Application filed April 18, 1929. Serial No. 356,097.

This invention relates to suction cleaners and particularly to dust bags for suction cleaners. More specifically it relates to dust bags which are made from paper, or other fibrous material.

5 The object of the invention is to provide a paper dust bag which has excellent filtering qualities and at the same time has sufficient tensile strength to stand up for a considerable time when used on a vacuum cleaner.

10 Another object is to provide a bag having portions thereof provided with a substantially open filtering material, and other portions made of a different filtering material which is substantially stronger than the first named material.

15 A further object is to provide a bag having portions thereof made of cotton felt and other portions made of paper, or other fibrous material, to provide the necessary tensile strength during normal use.

20 A still further object is to provide a dust bag which is made of paper, or other fibrous material and has portions thereof cut out which are filled in with a substantially open filtering material, such as cotton felt.

25 In accordance with the invention the dust bag is made of paper or other fibrous material. The bag has portions thereof cut away and strips of cotton felt are secured to the body of the bag to fill in that portion which has been cut away.

30 In the accompanying drawings which illustrate a selected embodiment of the invention the views are as follows:

35 Fig. 1 is a side elevation of a dust bag embodying the invention.

Fig. 2 is a similar view showing the dust bag in a modified form.

40 Fig. 3 is a detail sectional view on the line 3, 3 of Fig. 1.

Fig. 4 is a similar view on the line 4, 4 of Fig. 2.

45 Referring to the drawings, 5 designates generally the neck or discharge outlet of the suction cleaner upon which clamping means 6 is arranged for detachably securing the lower end of the dust bag 7 to the neck 5.

The bag 7 is preferably made of a fibrous material 8 such as paper, and is provided with

a plurality of slits or openings 9 which receive strips of cotton felt 10. The bag 7 may be creased along the lines 11 as shown, so that the bag may be collapsed to make a compact structure for shipping or storing. The end 12 of the bag is reduced as shown to provide a neck and may be reinforced by a collar 13. The bag is preferably provided with an open upper end 14 so that the bag may be easily emptied. The open end 14 may be closed by means of a clip 15, and flexible suspending means 16 are provided to secure the bag in proper position relative to the suction cleaner handle 17.

In Fig. 2, the paper bag 7 is cut away to provide an opening 18 which may be substantially one half the area of the entire bag, and this space is filled in with the cotton felt material 10 as clearly shown in Figure 4. The bag thus provided is practically the same as that mentioned above and is strong enough to be supported and carried by the cleaner and still provide excellent filtering characteristics. If the felt material were used without the means of reinforcement the bag would probably not have sufficient strength to stand the wear and tear when used on a suction cleaner.

The invention provides a dust bag which has sufficient tensile strength to stand up under ordinary usage for a considerable length of time and at the same time retain the filtering value which is characteristic of the cotton felt.

Changes may be made in the form, construction, and arrangement of the parts without departing from the spirit of the invention or sacrificing any of the advantages thereof and the right is hereby reserved to make all such changes as fairly fall within the scope of the following claims.

I claim:

1. A dust bag for suction cleaners, adapted for attachment at its ends to relatively movable parts of the suction cleaner, said bag being formed of air-porous sheet material extending the entire length of the bag and having an opening intermediate its ends, and a sheet of filtering material permanently secured to said bag and closing such opening.

2. A dust bag for suction cleaners, formed

of filtering material and adapted to be secured at its ends to relatively movable parts of the suction cleaner, said bag having an opening intermediate its ends, and a sheet of material 5 having a greater filtering capacity than the material of the body of said bag secured in said opening.

3. A dust bag for suction cleaners, formed of sheet material and adapted to be secured at 10 its ends to relatively movable parts of the suction cleaner, said bag having a plurality of longitudinally extending laterally spaced openings therein, and filtering material closing said openings, said openings being laterally spaced to leave strips therebetween to withstand the longitudinal stresses imposed upon the bag.

4. A dust bag for suction cleaners, formed of filtering material and having a plurality 20 of longitudinally extending laterally spaced openings therein terminating short of the ends of the bag, and filtering material having a greater filtering capacity than that of the material of the bag and of comparatively low 25 tensile strength secured to said bag to close said openings.

Signed at North Canton, in the county of Stark and State of Ohio, this 8th day of April, A. D. 1929.

30 WALTER C. DAVIDSON.
